UNITED STATES PATENT OFFICE.

GEORGE MURRAY, OF CAMBRIDGEPORT, MASSACHUSETTS.

REFRIGERATING APPARATUS.

1,167,591.

Specification of Letters Patent. Patented Jan. 11, 1916.

Application filed June 24, 1912. Serial No. 705,479.

To all whom it may concern:

Be it known that I, GEORGE MURRAY, a citizen of the United States, and a resident of Cambridgeport, in the county of Middlesex and State of Massachusetts, have invented an Improvement in Refrigerating Apparatus, of which the following description, in connection with the accompanying drawings, is a specification, like characters on the drawings representing like parts.

This invention relates to refrigerating apparatus for use in the manufacture of ice or for other purposes requiring the artificial production of low temperatures.

In order that the principles of the invention may be readily understood, I have disclosed a single embodiment thereof in the accompanying drawing, wherein—

Figure 1 is a side elevation of a refrigerating apparatus embodying my invention; Fig. 2 is a vertical transverse section upon the line 2—2 of Fig. 1; Fig. 3 is a top plan view of the said apparatus; and Fig. 4 is a transverse section upon the line 4—4 of Fig. 1.

In the artificial production of low temperatures, such, for example, as required in the manufacture of ice, it has been customary to pump or spray ammonia through pipes, the sprayed material ultimately collecting in liquid form and returning to the pump or circulating device to be re-distributed through the system. In the use of such apparatus a pump cylinder having therein a piston and a piston rod extending through a head of the cylinder has been commonly employed. The ammonia or other liquid or fluid escapes from the cylinder between the piston rod and head and thus interferes seriously with the proper operation of the apparatus.

In accordance with my invention, I provide a closed receptacle which is preferably hermetically sealed and position therein a gravity piston; that is to say, a piston having no external connection and operated solely by its own weight. I provide one or more suitable spraying means or inspirators within the said receptacle and operate them by the said piston, the ammonia or other suitable fluid being sealed within the receptacle or a chamber connected thereto. In the preferred embodiment of my invention, the receptacle is periodically inverted to

permit the piston to reciprocate by its own weight, and preferably the said receptacle is formed as a cylinder having trunnions in the line of its shorter axis, so that the cylinder may be constantly rotated end over end by hand or, and preferably, by a suitable motor. In this manner, the piston is moved to and fro within the cylinder by reason of its own weight, and alternately renders operative spraying devices positioned within the opposite ends of the cylinder.

Referring more particularly to the drawing, the cylinder is represented at 1, it being of any suitable material and dimensions. It is made sufficiently long to secure an effective length of movement of the piston. The said cylinder is provided with flanged ends 2, to which are bolted heads 3 secured to the cylinder in such manner as to hermetically seal the contents thereof. Within the cylinder is mounted a piston 4 preferably provided with a suitable circumferential packing 5 to afford a sufficiently tight sliding fit. Preferably the piston is heavily weighted with lead, the weight of the piston being such as to insure its proper to and fro movement upon rotation of the cylinder. Bolted to each head 3 of the cylinder and received upon a boss 6 thereon is a cap 7, said caps being removable but hermetically sealed in place, so as to prevent all escape of the ammonia or other refrigerating fluid.

Each head 3 is provided with a central opening 8 internally threaded at 9 to receive a sleeve 10 having a suitable number of ports 11 and itself internally threaded at 12 to receive a valve casing 13 within which is suitably guided for reciprocating movement a valve 14, preferably having a flat head and stem 15 received within said casing 13. The ports 11 communicate with the interior of the caps 11 and within the annular space 16 between the valve casing 13 and sleeve 10. The lower end of said valve casing 10 is provided with a horizontal flange 17 spaced sufficiently from the adjacent ends of the sleeves 10 to permit the discharge of the ammonia or other fluid from the caps through said ports 11, and the annular passage 16 into the adjacent end of the cylinder.

I provide suitable means to spray the ammonia or other fluid as it is discharged from the passages 16 into the cylinder. While this may be accomplished in any suitable

manner, I preferably effect this result by forcing a charge of vapor by means of the piston 4 into the field of the ammonia or other liquid, as it is discharged from the cap into the cylinder. For this purpose, I have represented two pipes 18 tapped into the flanges 2 of the cylinder. Viewing Fig. 2, it will be apparent that the left hand pipe 18 communicates at its upper end through a passage 19 in the upper flange 2 of the cylinder with a chamber 20 in the upper head 3. The said chamber 20 is provided with an annular discharge port 21 herein shown as positioned adjacent to and at substantially a right angle to the discharge end of the annular passage 16. The said port 21 is directed toward the piston 4, and the charge of vapor directed through said port 21 intercepts the ammonia or other liquid discharged through the passage 16 and sprays the same into the adjacent end of the cylinder.

At its opposite end the right hand pipe 18 is tapped or threaded into the flange 2 at the lower end of the cylinder, so as to communicate with a port 22 in said flange, said port communicating with the interior of the cylinder as shown. At its upper end the said pipe 18 is preferably provided with a ball valve 23 to prevent return of the charge therethrough.

The left hand pipe 18 is reversely connected to the flanges 2 of the cylinder and is provided with a ball valve 23 at its lower end. The construction of parts is, however, preferably substantially the same as that described with reference to the right hand pipe 18 and the operation is the same. The pipes 18 permit gas passing therethrough to heat up or vaporize liquid that may be carried into the cylinder 1.

The cylinder 1 may be inverted periodically in any suitable manner in order to compel the piston 4 to reciprocate therein. It is apparent that the cylinder might be oscillated in order to secure such to and fro movement of the piston, but preferably I provide means constantly to rotate the cylinder about its shorter axis, or, in other words, to turn the cylinder end over end. For that purpose I provide the cylinder with trunnions 24-24 in the line of its shorter axis, the said trunnions being mounted in any suitable support. In order to rotate the cylinder, I provide a suitable gear to be rotated by hand or if desired by a suitable motor.

It will be apparent that when the cylinder is inverted into the position shown in Fig. 2, the piston 4 drops from what is now the upper end to the lower end of the cylinder. The dropping of the piston compels an upward charge of ammonia vapor through the right hand pipe 18, thereby lifting the ball valve 23 and forcing said charge through

the passage 20. At the same time a partial vacuum or suction is created above the piston.

Before the caps 7 are sealed in position a suitable charge of ammonia, or other refrigerating liquid is placed in each cap. It will, therefore, be apparent that the vapor charge passing upward through the right hand pipe 18, will intercept the liquid ammonia passing by gravity down the passage 16 and will spray the same into the upper end of the cylinder, thereby chilling the cylinder. When the position of the cylinder is reversed, a similar action occurs at the other end thereof, so that the liquid is alternately sprayed at opposite ends of the cylinder thereinto with the refrigerating effect referred to.

It will be apparent that the ammonia sprayed into each end of the cylinder will collect in globules therein. It therefore becomes desirable to train the liquid ammonia from each end of the cylinder, as it is turned into the lowermost position, so as to permit the free descent of the piston 4 and to insure a suitable supply of ammonia for the next spraying action. To this end, I may drain the ammonia from each end in any suitable manner, but preferably I tap into each cap 7 the two ends 25-25 and 25'-25' of the two coils of pipes 26-26 and 27-27. The pipe coil 26 is connected only to the upper cap 7 and the pipe coil 27 is connected only to the lower cap 7. The said pipe coils pass one or more times longitudinally of and about the cylinder 1 and preferably at one side only of the trunnions 24. The other pipe coil 27 passes longitudinally of and about the cylinder, but upon the opposite side of said trunnions 24, whereby the two sides of the pipes balance each other.

It will be apparent that when the cylinder is in the position shown in Fig. 2, the then lower valve 15 drops away from its seat into contact with the interior of the head 7. This permits the liquid ammonia which may have formed or collected in the lower portion of the cylinder to pass into the cap, the ammonia also passing into the cap through the passage 16 and ports 11. The ammonia then passes into the pipes 25', 25', 27, 27, and is circulated therethrough during the rotation of the cylinder. As the position of the cylinder is reversed the ammonia is re-conveyed into the appropriate cap 7 so as to be sprayed therefrom, as previously described.

It will be apparent from the foregoing description that as the cylinder 1 is rotated upon its trunnions 24, the piston 4 gravitates from end to end and alternately forces charges through the pipes 18-18, the charge being composed of ammonia gas. Such charges intercept the liquid ammonia and spray the same alternately at the oppo-

site ends of the cylinder with the effect of cooling the cylinder wall. The chilling of the cylinder wall may be availed of in any suitable manner. For example, the cylinder 5 may rotate in or in contact with brine to be circulated through pipes to the place of use.

In order to remove from the apparatus heat generated by compression of the vapor, 10 I may employ flowing water. To this end I may apply any ordinary form of water jacket to the cylinder 1 and introduce and withdraw the water from said jacket through the trunnions or parts connected therewith. In Figs. 2 and 4, I have represented a water jacket composed of two metallic cylinders 28, 29 having between them a lining 30 of asbestos or mineral wool. This jacket may be of any suitable form 20 and applied in any suitable manner to the cylinder 1, and is provided with pipes 31, 32 extending through the trunnions 24 of the cylinder, thus establishing a suitable water circulation from any desired source. 25 This water jacket constitutes one form, of condenser suitable for removing all heat generated by compression in the operation of the apparatus into which the pipes 26, 27 extend.

30 Outside the cylinder 1 and its water jacket 28, 29, 30, I provide an outer inclosure 33 which rotates with the jacketed cylinder 1. To this end, the trunnions 24, 24 of the cylinder are formed with or extend from 35 said inclosure 33, and they are provided with inlet and discharge pipes 34, 35, by which brine or other suitable liquid may be introduced into the inclosure 33 and be discharged therefrom, thus establishing a 40 circulation. In this manner, the low temperature created in the operation of the apparatus results in the effective lowering of the temperature of the brine, which being circulated as desired may be used for cooling or refrigerating purposes.

The pipes 25, and if desired the pipes 25', may be provided with suitable check valves such as indicated at 36 to secure the proper circulation of the ammonia or other refrigerating medium.

The length of the pipe coils 26-27 and the internal diameter thereof are such that sufficient friction is produced for the compression and liquefying of the ammonia or other refrigerant employed. Thus applicant provides his apparatus with a high pressure portion,—namely the pipe coils 26-27—and a low pressure portion,—namely that into which each pipe coil 26 or 27 discharges. Owing to this construction no valves are necessary in the pipe coils 26-27 and the liquefied refrigerant is permitted to evaporate at a sufficiently low temperature when discharged from said pipe coils 26-27.

It is apparent that the apparatus is of simple construction, and that there is no leakage, inasmuch as the caps and heads are hermetically sealed in place.

Having thus described one illustrative embodiment of my invention, I desire it to be understood that although specific terms are employed, they are used in a generic and descriptive sense and not for purposes of limitation, the scope of the invention being set forth in the following claims.

Claims:

1. A refrigerating apparatus comprising a rotatable receptacle, pipes connecting opposite ends thereof, and means operated by the rotation of said receptacle to spray a refrigerating liquid in said receptacle.

2. A refrigerating apparatus comprising an hermetically sealed cylinder, pipes connecting opposite ends thereof, a gravity piston in said cylinder, and spraying devices between which said piston reciprocates.

3. A refrigerating apparatus comprising a closed cylinder rotatable end over end, pipes connecting opposite ends of said piston, and alternatively operative spraying devices within said cylinder and between which the piston reciprocates.

4. A refrigerating apparatus comprising a closed cylinder rotatable about its shorter axis, a pair of pipes connecting the ends of said cylinder, a terminal spraying device in communication with each pipe, and means for projecting spraying charges alternately through said pipes.

5. A refrigerating apparatus comprising a closed cylinder rotatable about its shorter axis, refrigerating liquid containing caps secured to opposite ends of said cylinder and communicating therewith, a plurality of pipes connecting opposite ends of said cylinder through said caps and means to spray the liquid discharged from said caps into said cylinder.

6. A refrigerating apparatus comprising an hermetically sealed vessel, a refrigerating liquid containing chamber in communication therewith, devices connecting the opposite end thereof, and means to spray liquid discharged from said chamber into said vessel.

7. A refrigerating apparatus comprising an invertible hermetically sealed receptacle, pipes connecting opposite ends thereof and means rendered operative by the inversion of said receptacle to spray refrigerating liquid within said receptacle.

8. A refrigerating apparatus comprising an invertible, closed receptacle, pipes connecting opposite ends thereof a spraying device rendered operative by the inversion of said receptacle, and means to drain refrigerating liquid from said receptacle.

9. A refrigerating apparatus comprising an invertible, hermetically sealed cylinder,

pipes connecting opposite ends thereof a gravitating piston therein, spraying devices operated by said piston and between which it reciprocates, and means to drain liquid alternately from the cylinder ends.

10. A refrigerating apparatus comprising an invertible, hermetically seated cylinder, pipes connecting opposite ends thereof a gravitating piston therein, spraying devices operated by said piston and between which it reciprocates, and means to drain liquid

from each cylinder end when it is lowermost and to return it thereto when it is uppermost.

In testimony whereof, I have signed my 15 name to this specification in the presence of two subscribing witnesses.

GEORGE MURRAY.
